UNITED STATES PATENT OFFICE.

HENRY G. VOIGHT, OF NEW BRITAIN, CONNECTICUT, ASSIGNOR TO SARGENT & COMPANY, OF NEW HAVEN, CONNECTICUT, A CORPORATION OF CONNECTICUT.

LOCK.

1,241,788.

Specification of Letters Patent.

Patented Oct. 2, 1917.

Application filed March 27, 1917. Serial No. 157,637.

To all whom it may concern:

Be it known that I, HENRY G. VOIGHT, of New Britain, county of Hartford, State of Connecticut, have invented certain new and useful Improvements in Locks, of which the following is a full, clear, and exact description.

This invention relates to locks, and it has particular reference to mortise locks having both a latch bolt and a dead bolt. The invention also has particular reference to locks of this type in which the "backset" is very narrow, but in which, nevertheless, a cylinder lock is not only arranged to operate the dead bolt but also to retract the latch bolt.

In a lock of this character, where the available space is very small, it is of the greatest importance to have the working parts simple and readily accessible, and this is one of the primary objects of the invention.

Another object of the invention is to furnish a lock in which the operation of the dead bolt from the inside of the door by means of a thumb knob is very efficient and reliable.

To these and other ends, the invention consists in the novel features and combinations of parts to be hereinafter described and claimed.

In the accompanying drawing,

Figure 1 is a front elevation of a lock embodying the invention, with the cap plate removed showing the parts in the normal position.

Fig. 2 is a similar view showing the latch bolt retracted by the cylinder lock mechanism.

Fig. 3 is a fragmentary view of the lock, showing the dead bolt in the protracted position.

Fig. 4 is a reverse view of the upper part of the lock, partly in section, through the case.

Figs. 5 and 6 are detail sections on lines 5-5 and 6-6, respectively, of Fig. 1.

Fig. 6^a is a section on line 6^a-6^a of Fig. 6.

Fig. 7 is a detail elevation of the bolt.

Fig. 7^a is a top plan view of the bolt.

Fig. 8 comprises detail views of the sliding tumbler.

Fig. 9 is a detail of the latch-actuating slide.

Fig. 10 is a fragmentary inside view of the cap plate, showing the thumb turn hub.

The mortise lock case 11, which has a very narrow backset, is provided with a spring-pressed latch bolt 12, and, above the latch bolt, with a dead bolt 13. The latch bolt 12 has a stem 14 surrounded by the usual 60 spring 15, and at the rear end of the stem is a cross-head 16 adapted to be engaged by a retracting lever 17.

This retracting lever 17 can be actuated in the customary manner by suitable knob-controlled mechanism, which it is not necessary to refer to in further detail inasmuch as the same forms no part of my invention. Above the dead bolt, a cylinder lock 18, of the usual type, is screwed into the 70 case at the outside of the door. The cylinder is provided with an ordinary cam, or rollback, 19, by means of which the dead bolt 13 may be protracted and retracted. The dead bolt is suitably guided on the rear wall 75 of the case 11 and, at its rear portion, is furnished with talons 20 to be engaged by the rollback 19. Intermediate these talons, the shank of the dead bolt is cut away to form a guideway 21 in which a tumbler 22 is vertically movable. Projecting out from the guideway is a pin, or post, 23, which passes through a slot 24 in the body of tumbler 22 and serves to limit the up and down movement of said tumbler, in its guideway, as 80 will be understood. At its lower part, the tumbler carries a stump, or lug, 25, extending rearwardly therefrom and adapted to co-operate with a fence 26 on the back of the case. It will be understood that the guideway 21 and the tumbler 22 are located at the front of the bolt-shank, where the tumbler is readily accessible. When the bolt is in the retracted position, the lug 25 stands behind the fence 26, and when the bolt is protracted, the lug stands in advance of said fence.

A spring 27 embracing a pin 28, on the rear portion of the dead bolt, normally maintains the tumbler at the limit of its upward movement, in which position the 100 lug co-operates with the fence to lock the bolt, either in the retracted or protracted position, but the tumbler can be depressed to release the bolt by the rollback 19 which engages the upper part of the tumbler between and in line with the talons 20. The spring 27 acts against a projection 29 at the upper part of the tumbler located adjacent to the bolt talons but in a plane parallel to that of said talons. This projection 110

29 is straddled by the legs 30 of a thumb turn hub 31 rotatably mounted on a plate 32 detachably secured by a screw 33 in an opening 34 in the cap plate 35, as shown 5 in Fig. 10. The hub 31, by straddling the projection 29 is adapted not only to depress the tumbler as the hub is turned, but also to protract and retract the bolt. The opening 34 is adapted to receive a cylinder lock, 10 similar to lock 18, when the plate 32 is removed, and it will be understood that the lock can be reversed by interchanging the cylinder and hub plate 32 in the respective openings. When these parts are interchanged, the thumb turn hub 31 will be located at the back of the case, the cylinder lock being mounted on the cap plate in this 15 instance; and the hub 31 will coöperate with an operating projection 29^a formed on the 20 back side of tumbler 22. This projection 29^a is similar to the projection 29 and in line therewith, the rollback-engaging portion of the tumbler being located between the two 25 projections.

25 By the construction described, the dead bolt may be very readily and reliably operated by the thumb knob. As the hub 31 straddles one of the tumbler projections when the parts are assembled and cannot 30 move out of operative relation thereto, the construction is very simple and efficient, and yet it permits ready reversal to change the hand of the lock. The hub-carrying plate 32 overhangs the opening 34 at the inside, as 35 shown at 36, so that only one fastening screw 33 is necessary for securing the plate removably in the ordinary cylinder lock opening. The movement of the hub is limited to a quarter-turn by shoulders 37 on the plate.

40 The latch bolt 12 can be retracted by the rollback 19 through a slide member 38 mounted on the dead bolt and actuating a retracting lever 39. The lever 39 is pivoted on the post 23, which serves to guide the 45 tumbler 22, and the lower end of lever 39 is adapted to engage the cross-head 16 to retract the latch bolt. In doing this, the slide 38 is depressed by the rollback 19 and a pin 39^a on said slide engages the upper arm of lever 39 and depresses the same to effect 50 the retraction of the bolt as shown in Fig. 2. The latch bolt actuating slide 38 is guided vertically on the dead bolt, alongside but in advance of the sliding tumbler 22. It has a guideway 40 in the dead bolt, and, at one side of the guideway 40 and in the head of the bolt is a socket 41 in which a plunger 42 on the slide 38 is guided. Between the bottom of plunger 42 and the bottom of the socket 41, is 55 a coil spring 43 which normally holds the slide 38 in the elevated position shown in Fig. 1. When the parts are in this position, the head of the plunger portion 42 of the slide is close to and in the path of the rollback 19, 60 so that when the latter is turned in a counter-

clockwise direction the slide 38 will be depressed to retract the latch bolt through the connections previously described, as shown in Fig. 2. When the rollback is turned to the initial position, the spring 43 protracts the latch bolt again, and the spring 43 carries the slide 38 to its initial position. 70

It will be observed that both the sliding tumbler and the sliding latch-actuating member are mounted in guides just beneath 75 the cap plate of the case where they are very readily accessible, and that the parts are simple so that they can be readily manufactured and assembled.

The cylinder lock rollback 19 and the thumb turn hub or rollback 31 are substantially in line with each other, which simplifies the construction of the lock and permits its ready reversal. 80

While I have described my invention as 85 being particularly applicable to a lock with a narrow backset, it will be obvious that various changes in the details of the construction may be made without departing from the scope of the invention as set forth in the 90 claims.

What I claim is,

1. In a lock, a case, a latch bolt therein, a dead bolt in the case above the latch bolt, a slide mounted in said dead bolt to move up 95 and down, a pivot pin mounted on the bolt, a lever pivoted on said pivot pin and operated by said slide to retract the latch bolt, a cylinder lock mechanism to actuate said slide, a fence for the dead bolt, and a vertically 100 sliding tumbler on the dead bolt to coöperate with said fence guided on said pivot pin.

2. In a lock, a casing, a latch bolt therein, a dead bolt above the latch bolt, having a 105 socket at the upper part thereof, a plunger in said socket, having a downward extension guided in a groove on the outer face of the dead bolt, a spring interposed between said plunger and the bottom of the socket in the dead bolt, a cylinder lock having a rollback adapted to engage and depress said plunger, and retracting mechanism for said latch bolt, operatively connected with the lower part of said plunger extension. 110

3. In a lock, a case, a dead bolt therein, a fence on the case below said dead bolt, a vertically sliding tumbler guided on said bolt, talons on the bolt at opposite sides of said tumbler, a cylinder lock to operate said bolt by coöperation with said tumbler and said talons, and a thumb turn hub at the side of the case opposite said cylinder lock, constructed to straddle said tumbler and to operate said bolt thereby independently of 120 said talons. 115

4. In a lock, a case, a dead bolt therein, a fence on the case below said dead bolt, a vertically sliding tumbler guided on said bolt, talons on the bolt at opposite sides of 130

5 said tumbler, a cylinder lock to operate said bolt by coöperation with said tumbler and said talons, and a thumb turn hub at the side of the case opposite said cylinder lock, 10 constructed to straddle said tumbler and to operate said bolt thereby independently of said talons, said cylinder lock and said thumb turn hub being interchangeable and said thumb turn hub being operative on said 15 tumbler when said hub is located at either side of the case.

5. In a lock, a case, a latch bolt therein, a dead bolt in said case above the latch bolt, having talons at the upper part thereof, a 15 vertically sliding tumbler on said bolt between said talons, a fence beneath said bolt to coöperate with the lower portion of said tumbler, a cylinder lock at one side of the case, having a rollback to coöperate with said 20 tumbler and said talons, a thumb turn hub at the opposite side of the case straddling the top of said tumbler, a post on said dead bolt on which said tumbler is guided by a 25 slot in the latter, a latch retracting lever pivoted on said post, and means for operating said lever from said rollback.

6. In a lock, a case, a latch bolt therein, a dead bolt in said case above the latch bolt, having talons at the upper part thereof, a 30 vertically sliding tumbler on said bolt between said talons, a fence beneath said bolt to coöperate with the lower portion of said tumbler, a cylinder lock at one side of the case, having a rollback to coöperate with said 35 tumbler and said talons, a thumb turn hub at the opposite side of the case straddling the top of said tumbler, a post on said

dead bolt on which said tumbler is guided by a slot in the latter, a latch retracting lever pivoted on said post, and means for operating 40 said lever from said rollback, said cylinder lock and thumb turn hub being interchangeable to reverse the hand of the lock.

7. In a lock, a case, a dead bolt therein, having talons at the upper part thereof, a 45 vertically sliding tumbler guided on said bolt between said talons, a fence in the case to coöperate with said tumbler, a cylinder lock at one side of the case having a rollback to engage said talons and the top of said 50 tumbler between said talons, a projection at the upper part of said tumbler lying in a plane parallel to that of said talons, and a thumb turn hub straddling said projection.

8. In a lock, a case, a dead bolt therein, 55 having talons at the upper part thereof, a vertically sliding tumbler guided on said bolt between said talons, a fence in the case to coöperate with said tumbler, a cylinder lock at one side of the case having a rollback to engage said talons and the top of said 60 tumbler between said talons, a projection at the upper part of said tumbler lying in a plane parallel to that of said talons, a thumb turn hub straddling said projection, 65 a carrying member for said thumb turn hub, said cylinder lock and carrying member being interchangeable for reversing the hand of the lock, and a second projection on the upper part of the tumbler to engage said 70 thumb turn hub when the lock is reversed.

In witness whereof, I have hereunto set my hand on the 24th day of March, 1917.

HENRY G. VOIGHT.
